By his Attorney

L. Stark DeMentor

UNITED STATES PATENT OFFICE.

HERBERT ABRAHAM, OF NEW YORK, N. Y., ASSIGNOR TO THE RUBEROID COMPANY,
A CORPORATION OF NEW JERSEY.

SHINGLE.

Application filed November 15, 1920. Serial No. 424,061.

To all whom it may concern:

Be it known that I, HERBERT ABRAHAM, a citizen of the United States, residing at the city, county, and State of New York, have 5 invented certain new and useful Improvements in Shingles, of which the following is a specification.

This invention relates to improvements in shingles made of so-called "prepared roofing," and has for its object to provide a roof covering whereby an illusion of shadows is produced along the exposed ends or butts of the shingles. According to my invention I provide a shingle which may be 10 laid with either end exposed and which is provided on its surface with two parallel, transverse, narrow black stripes, so disposed that when a plurality of such shingles are laid in overlapping courses an appearance of shadows is produced along the exposed ends of the shingles.

While prepared roofing shingles are both economical and efficient, the greatest objection to their use resides in their thinness 25 and the consequent lack of the desired ornamental appearance of massiveness of a roof covering composed of such shingles. My invention overcomes this disadvantage by producing an illusory effect of increased thickness.

In my pending application, Serial No. 341,791, filed Dec. 1, 1919, I have shown and described a shingle having a band of contrasting color extending transversely across 35 the middle of its surface, the edges of which serve as gauge marks for laying the shingles with either end exposed, and which bands produce a shadow effect in the spaces between the sides of the exposed portions of 40 adjacent shingles.

My present improvement is particularly applicable to such shingles, and when thus applied results in producing shadow effects along the ends, as well as at the sides, of the 45 exposed portions of the shingles, thus causing said portions to apparently stand out in bold relief and thereby obtaining a very attractive and ornamental appearance.

In the accompanying drawings:

50 Figure 1, represents a shingle embodying my invention; and,

Fig. 2 is a perspective view of a section of a roof partly covered with such shingles.

Referring to the drawings, 1 represents a 55 shingle composed of prepared roofing, that

is, made of a material consisting of roofing felt saturated or impregnated with a suitable bituminous composition. The shingle is preferably provided with a band 2 of contrasting color extending transversely across 60 the middle of its face, as described in my pending application, Serial No. 341,791, filed Dec. 1, 1919.

Disposed above and below the edges of the band 2, and extending parallel to said 65 edges, are a pair of narrow stripes 3—3 which are formed of dark coloring matter applied to the face of the shingle. The stripes 3 are sufficiently wide, preferably $\frac{1}{2}$ ", so as to produce the effect of shadows along 70 the butts of the shingles when a plurality of such shingles are laid in overlapping courses, and they are preferably spaced about $\frac{1}{8}$ " from the edges of the band 2 so as to leave lines 4, free from extraneous coloring matter, between said parts.

The provision of the two stripes 3—3 makes the shingle reversible endwise. If desired the stripes may be applied to both surfaces so as to permit also of facial reversibility. Furthermore, it is to be understood that the shingle may be surfaced with particles of crushed slate or other suitable surfacing material.

In laying a roof covering with my improved shingles, I first lay a row, such for example as the row A, and then align the butt ends of the shingles in the succeeding row B with the unpainted line 4 at the exposed ends of the shingles in row A. It will 90 be seen, therefore, that the unpainted lines 4 serve as guages for properly laying the shingles, and that when thus laid the dark stripes 3 will extend beyond the butts and will simulate shadows.

While I prefer to provide the shingles with the intermediate bands 2, so as to produce an illusion of shadows between the side edges of adjacent shingles, as seen in Fig. 2, I do not limit my invention in this respect. If desired the shingles may be made without bands 2, in which event the inner edge of one or the other of the stripes 3, depending upon which end of the shingle is exposed, will serve as a guage mark for 105 the butt of the superposed shingle.

What I claim is:

1. A prepared roofing shingle having two transverse stripes in substantially the middle third portion, the innermost edges of the 110

stripes being located inward from the upper and lower shingle-edges respectively, substantially the distance that the shingle-ends are intended to be exposed when laid, said 5 stripes being of a dark color and contrasting with the color of the shingle-ends.

2. A prepared roofing shingle having two transverse stripes and an intermediate band in substantially the middle third portion, 10 the innermost edges of the stripes being spaced slightly from the proximate edges of the band and being located inward from the upper and lower shingle-edges respectively, substantially the distance that the shingle-ends are intended to be exposed when laid, 15 said stripes and band being of dark color and contrasting with the color of the shingle-ends.

3. A roof covering comprising a plurality of prepared roofing shingles each having 20 two transverse stripes in substantially its middle third portion, the innermost edges of the stripes being located inward from the upper and lower shingle-edges respectively, substantially the distance that the shingle-ends are intended to be exposed when laid, 25 said stripes being of a dark color and contrasting with the color of the shingle-ends, said shingles being laid in overlapping courses with either end exposed indiscriminately, and with the butts of the shingles of each overlying course bordering on the stripes of the exposed ends of the shingles of each underlying course, whereby to produce a simulation of shadows along the butts. 30 35

HERBERT ABRAHAM.
